BALL POINT PEN

Clarence D. Zierhut, Granada Hills, Calif., assignor to
Paper Mate Manufacturing Company, Santa Monica,
Calif., a corporation of Delaware

Filed Jan. 26, 1961, Ser. No. 63,707

Term of patent 14 years

(Cl. D74—17)

FIG. 1.

FIG. 2.

FIG. 3.

FIG. 4.

FIG. 1 is a front elevational view of a ball point pen, showing my new design;

FIG. 2 is a side elevational view thereof, the opposite side being substantially the same in appearance;

FIG. 3 is a top plan view of the ball point pen shown in FIG. 1; and

FIG. 4 is a bottom plan view thereof when the pen is rotated at an angle of 180°.

The essential features of my design reside in the portions shown in solid lines on the drawing.

I claim:

The ornamental design for a ball point pen, as shown and described.
